UNITED STATES PATENT OFFICE

2,601,939

CAN HOLDER AND PUNCH

Merle L. Grob, Peoria, Ill.

Application January 6, 1949, Serial No. 69,468

1 Claim. (Cl. 222—86)

1

The present invention relates to new and useful improvements in can holders and punches and embodying a dispensing receptacle in which a can may be placed for serving the contents directly from the can.

An important object of the invention is to provide a receptacle or shell for placing over a can and embodying means for puncturing the can as the shell is placed thereon, for pouring the contents of the can directly therefrom by means of a spout formed with the shell and also for venting air from the can to facilitate pouring of the contents.

A further object of the invention is to provide a dispensing holder and punch for a can which completely encloses the can, which possesses a neat and attractive appearance to enhance its desirability for table use, and which, at the same time, is relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view;

Figure 2 is a vertical sectional view;

Figures 3 and 4 are transverse sectional views taken respectively on the lines 3—3 and 4—4 of Figure 2;

Figure 5 is a fragmentary sectional view taken on a line 5—5 of Figure 3; and

Figure 6 is an enlarged detail of the interlocking connection between the shell and its base.

Referring now to the drawing in detail wherein, for the purpose of illustration, I have disclosed a preferred embodiment of the invention, the numeral 5 designates a shell having a top 6 integrally formed therewith and open at its bottom for resting on a bottom flange 7 of a ring-like base 8.

The outer surface of the shell 5, adjacent its lower edge, is formed with a plurality of locking lugs 9 received in a bayonet slot 10 on the inner side walls of the base 8, the slot 10 having an inclined upper edge 11 under which the lug 9 rides to pull the shell downwardly as the lug enters the entrance 12 of the slot and the shell 5 and base 8 then turn relative to each other to lock the lug in the slot in a usual manner.

A spout 13 projects upwardly at one side of the top 6 of the shell and to which a hollow punch 14 is connected to extend downwardly in the

2

shell, the lower edge of the punch being bevelled to form a can-penetrating prong 15.

A vent opening 16 is also formed in the top 6 at a diametrically opposite side from the spout 13 and to which is also attached a hollow punch 17 which also extends below the top 6 and is also formed with a can-penetrating prong 18. Gaskets 19 are provided for the punches 14 and 17 and are held thereon at the under side of the top 6.

In the operation of the device, the shell 5 is removed from base 8 and a can 20 placed in the base to rest on the flange 7 and the shell 5 is then placed over the can and forced downwardly to cause the punches 14 and 17 to penetrate the top of the can. The openings formed in the top of the can by the punches are sealed by the gaskets 19.

The shell 5 with the can positioned therein is then turned in base 8 to lock the shell to the base and the can is thus firmly held in the shell during handling thereof while pouring the contents of the can from the spout 13.

To facilitate removal of the can from shell 5, finger openings 21 are formed at diametrically opposite sides in the lower edge of the shell for gripping the can after first removing base 8, and then pulling the can downwardly to free the top of the can from the punches 14 and 17.

The base 8 is formed with inwardly projecting lugs 22 to center the can on the base.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claim.

Having described the invention, what is claimed as new is:

A can punch and pouring dispenser comprising a base ring for seating a can, a shell closed at its top and having an open bottom for positioning of the shell downwardly over the can and into the ring and for removal of the can out of the shell when the shell is removed out of the ring, a hollow punch in the top of the shell for punching the can, internal bayonet slots in said ring each having an upwardly opening end

and an inclined upper edge, bottom lateral lugs carried by the shell for positioning downwardly in the open ends of the slots and rotation against the upper edges of said slots by rotation of the can whereby to lock said shell in said ring, said shell having bottom edge finger openings therein for gripping the can to pull the same out of the shell, said openings being hidden from view by the ring when the bottom of the shell is positioned in the ring.
